UNITED STATES PATENT OFFICE.

DANIEL O. SWAN, OF LOWELL, MASSACHUSETTS.

TOBACCO-PIPE ATTACHMENT.

Application filed July 29, 1926. Serial No. 125,780.

This invention relates to smokers' appliances and more particularly to a tobacco supporting and draft regulating attachment for a pipe.

5 One object of the invention is to provide an attachment which may be removably fitted into the bowl of a pipe and support the tobacco above the draft passage of the stem and prevent clogging of the passage and 10 also cause the tobacco to burn evenly when air is drawn through the bowl and stem of the pipe.

Another object of the invention is to permit a tobacco supporting disk forming a 15 portion of the attachment to be readily forced downwardly into the bowl of the pipe and have close fitting engagement with the walls thereof and assume a concavo-convex shape when in place.

20 Another object of the invention is to provide a device of this character which may be stamped from pliable sheet metal and very cheaply produced.

The invention is illustrated in the 25 accompanying drawing, wherein

Figure 1 is a sectional view showing the attachment applied to a pipe;

Fig. 2 is a perspective view of the attachment, and

30 Fig. 3 is a view showing the attachment in front elevation before it is applied to a pipe, a portion of its handle being broken away.

The attachment constituting the subject-matter of this invention is preferably 35 formed of pliable sheet metal, although other materials may be employed and includes a tobacco supporting disk 1 having a handle or shank 2 extending therefrom, as shown in Fig. 2. The disk 1 is provided 40 with a diametrically extending slit 3 which terminates adjacent the lower end of the shank or handle and divides the disk into companion side sections 4 which are adapted to have their adjacent side portions over- 45 lapped, as shown in Fig. 3. A plurality of openings 5 are formed in the side sections of the disk so that air may be freely drawn into the smoke passage 6 of the stem 7 of a pipe having the attachment fitted into its

50 bowl 8, as shown in Fig. 1. Referring to Figs. 1 and 2, it will be seen that the openings decrease in size from the free ends of the sections 4 towards their joined ends at

the base or lower end of the shank 2. This causes the air to pass more freely through 55 the portions of the disk farthest from the smoke passage 6 and, therefore, the tobacco will be caused to burn evenly instead of the major portion of the consumption taking place at the side of the bowl from which the smoke passage and stem extend. The disk is normally slightly larger than the bowl of the pipe with which it is intended to be used but not of sufficient size to prevent it from being forced downwardly to the position 60 shown in Fig. 1. Pressure applied to the disk in order to force it downwardly into place will cause the adjacent side portions of the sections 4 to slide over each other and at the same time the central portion of the 65 disk will be depressed so that the disk assumes a concavo-convex shape. The marginal edges of the disk will have close fitting engagement with the walls of the bowl so that it will be firmly held in place and 70 tobacco and its resulting ashes prevented from working downwardly beneath the disk. The disk is limited in its downward movement by the bill or hook 9 at the upper end of the shank 2 and when in place supports 75 the tobacco above the draft passage 6. It will thus be seen that tobacco pressed into the bowl will be prevented from clogging the smoke passage and that air may be 80 freely drawn through it. While the suction 85 in the bottom of the bowl is naturally greater at the side thereof from which the stem and its smoke passage extend the provision of the large and small openings in the disk will cause the suction to be evenly 90 distributed in the bowl and the tobacco evenly consumed. After the tobacco has been all reduced to ashes, the attachment may be drawn outwardly through the medium of its shank or handle and the ashes 95 will be removed and the walls of the bowl scraped clean. While the attachments are to be made for use in connection with pipes having bowls of approximately the same size, it will be readily understood that, since 100 the disk is slit, it may accommodate itself to bowls which vary somewhat in diameter.

Having thus described the invention, I claim:

A tobacco pipe attachment comprising a 105 normally flat disk formed with draft pas-

sages, a shank extending upwardly from the periphery of said disk, said disk being provided with a slit extending diametrically across the disk and terminating adjacent the lower end of said shank intermediate the width thereof and dividing the disk into companion sections joined adjacent the base of the shank, said sections be-

ing overlapped and adapted to be moved transversely of each other and bowed to produce a concavo-convexed disk when forced into a pipe bowl. 10

In testimony whereof I affix my signature.

DANIEL O. SWAN. [L. s.]
